M. Hayes
ATTORNEY

in brackets 33 and 34 which are secured to the stripper roll supports of the machine by suitable fastening means 36. The cylinder is substantially coextensive in length with roll 12 and is rotatable about its longitudinal axis. The axis of rotation of cylinder 30 is substantially parallel to the axis of rotation of copying roll 12. Along the length of the cylinder, there is provided a narrow slot in which is inserted a flat slab 38 of rubber sponge or other suitable material. The sponge extends radially outward from the cylinder and, as shown in Fig. 2, extends diametrically across the interior of the cylinder. The sponge 38 is maintained in position within the slot by screws 39 which are angularly secured along the edges of the slot. A handle 40 is secured to stub shaft 32 by which the cylinder can be rotated about its axis in the manner shown in Fig. 3. It is to be understood that this method of securing the sponge in the cylinder is only illustrative of one form the invention may take, and that other means, for example, a quick release clamp, may be used to hold the sponge.

Referring now to Fig. 2, the cleaning device and means for supplying cleaning and moistening fluid thereto is shown in greater detail. It will be noted that stub shaft 31 is hollow, there being inserted therein a small perforated tube 42 which extends downward along the left end of the cylinder 20 and then along the entire length of the cylinder 30. Liquid is supplied through this tube from a liquid reservoir 50, certain features of which will hereinafter be described in more detail. The purpose of the perforated tube is to insure equal distribution of fluid throughout the length of the cylinder 30, thereby to prevent one end of the sponge from becoming more saturated with liquid than the other. This feature is of considerable importance when liquid is first introduced to the device, since after it has been in operation for some time the liquid fills the cylinder to a predetermined level which is automatically maintained by means now to be described.

Referring now to Figs. 1 and 2, there is illustrated a liquid reservoir which may consist of bottle 50 supported at a convenient place on the frame of the duplicating machine. Directly below the bottle there is provided a liquid level control valve 51 from which a pipe 52 conducts the liquid to the interior of the cylinder. A suitable rotating joint 53 is provided in the liquid conducting pipe to allow rotation of the cylinder 30 relative to the liquid conducting means. A valve 54 is provided in the liquid conducting means to shut the water off from the cylinder when the machine or the cleaning device is not in use. The liquid level control valve 51 is of a conventional type which includes a spring loaded plunger 60 for closing the container when it is not in use. As shown in Fig. 2, the plunger is moved upward when the bottle is set onto the well 61 thereby to allow liquid to flow from the bottle into the plumbing 52 to the cleaning device. However, when the liquid in the system reaches a level which is higher than the point 62 at the end of tube 63, which is attached to the cap of bottle 50, further liquid is prevented from flowing out and the liquid level in the system is automatically maintained at that level. The liquid supplying system is simple in construction and automatic in operation, thus requiring little, if any, attention or maintenance.

The operation of the cleaning device will be clearly understood by reference to Figs. 1 and 3. As shown in Fig. 1, the device is in its inopera-

tive position, the handle 40 being pushed backward to rotate cylinder 30 to a position where sponge 38 is out of contact with the copying film 23 on the roll 12. The same inoperative position is also shown in Fig. 3 by the full line position of arm 40. As more clearly shown in Fig. 3, cylinder 30 is so spaced from the periphery of the roll 12 and spongelike member 38 extends such a distance radially from cylinder 30 that movement of handle 40 through an arc of approximately 90° to its operative position (shown by dotted lines), causes the sponge to contact film 23 on the copying roll 12. With the handle held in its operative position, the copying roll is made to rotate whereby the entire surface of the film is quickly and uniformly cleaned by a simple and safe operation. The handle 40 is of such a length that the operator's hand during the manipulation thereof is at a safe distance from all moving parts of the machine whereby all danger of injury is obviated. When the roll is sufficiently moistened or cleaned, the handle is swung back and left in its inoperative position until further use of the cleaning device is required. The liquid remains within the cylinder, and because of the substantially upright position of the sponge while in its inoperative position, there is no possibility of the water leaking out of the cylinder. Accordingly, the cleaning device is always in condition for immediate use, no time being required to saturate the sponge before starting each cleaning operation.

It will be apparent from the foregoing description that there is provided a device which will effectively and quickly clean the film of a copying roll of a duplicating machine without danger to the hands of the operator of the machine.

Although the invention has been described in combination with a duplicating machine having a rotating copying roll, it will be apparent to one skilled in the art that the device is equally applicable to duplicating machines having a flat, reciprocating copying roll on which the film is carried. It will also be apparent that minor structural changes may be necessary to adapt the device to rotating machines of other models than the one illustrated in the drawings. It is accordingly desired that the scope of the invention be limited only by the appended claims.

The invention described herein may be manufactured and used by or for the Government of the United States of America for government purposes without the payment of any royalty thereon or therefor.

What is claimed is:

1. A device for cleaning and moistening the film carried on the rotating copying roll of a duplicating machine having stripper roll supports, said device comprising, a hollow cylinder closed at its ends being mounted on said machine with its axis parallel to the axis of rotation of said roll and with its outer surface spaced from the outer surface of said film a predetermined distance, said cylinder having stub shafts positioned on the axis of said cylinder and extending from the closed ends thereof, a pair of brackets mounted on the stripper roll supports of said machine, said shafts being journaled in said brackets whereby said cylinder may be rotated about its axis, said cylinder having a narrow longitudinal slot cut therein of a length substantially coextensive with the width of said film, a flat spongelike member secured in said slot and extending radially outward from said cylinder a distance greater than said predetermined distance and also extending into

said cylinder across the diameter thereof, a perforated tube positioned within said cylinder and extending along an internal surface thereof diametrically opposite said slot, a liquid reservoir mounted on said machine, a pipe having a rotatable joint therein connecting said reservoir and said perforated tube, means for maintaining a constant liquid level within said cylinder, and a handle secured to one of said stub shafts for selectively rotating said cylinder from an angular position where the plane of said spongelike member is substantially vertical and out of contact with said film to a position where the plane of said spongelike member is substantially horizontal and the extremity of the radial extension thereof is in contact with said film.

2. A device for cleaning and moistening the film carried on the rotating copying roll of a duplicating machine having stripper rolls associated with said copying roll and supports for said stripper rolls, said device comprising a hollow cylinder closed at its ends, a pair of stub shafts extending axially from the closed ends of said cylinder and rotatably mounted on said stripper roll supports to position the axis of said cylinder parallel to the axis of rotation of said copying roll and to space the outer surface of said cylinder a predetermined distance from said film, a flat sponge member coextensive with said copying roll extending diametrically across said cylinder and protruding radially from said cylinder a distance slightly greater than said predetermined distance, means for uniformly distributing liquid along the length of said sponge, and a handle secured to one of said stub shafts for rotating said cylinder about its axis through an angle from an inoperative position where the plane of said sponge is substantially vertical and the protruding portion of said sponge is directed upward to a position where the plane of said sponge is substantially horizontal and the radial extremity thereof is in contact with said film.

3. A device for cleaning and moistening the film carried on the rotating copying roll of a duplicating machine having stripper rolls associated with said copying roll and supports for said stripper roll, said device comprising, a pair of brackets mounted on the stripper roll supports of said machine, a hollow, closed, elongated cylinder having stub shafts extending axially from the ends thereof rotatably journaled on said brackets whereby said cylinder may be rotated about its axis, said brackets being arranged to space the outer surface of said cylinder a predetermined distance from said copying roll and parallel to the axis of rotation of said roll, said cylinder having a narrow longitudinal slot cut therein of a length substantially coextensive with the width of said film, a spongelike member positioned coextensively within said slot and extending radially outward from said cylinder a distance greater than said predetermined distance and also extending into said cylinder across the diameter thereof, a perforated tube extending along an internal surface of said cylinder diametrically opposite said slot, a handle secured to one of said stub shafts for selectively rotating said cylinder through an

angle of approximately 90° from an inoperative position where a plane including said slot and said tube is substantially vertical and said spongelike member is directed upward to a position where said plane is substantially horizontal and the radially extending portion of said spongelike member is in contact with said film, and means mounted on said machine and connected to said tube for supplying and maintaining liquid in said cylinder at a level below the axis of said cylinder.

4. A device for cleaning and moistening the film carried on the rotating copying roll of a duplicating machine comprising, in combination, 15 a pair of brackets secured to said machine at opposite ends of said copying roll, a hollow, elongated cylinder closed at its ends, a pair of stub shafts coaxially extending from the closed ends of said cylinder and being rotatably journaled on 20 said brackets, said brackets being arranged on said machine to position the axis of said cylinder parallel to the axis of rotation of said copying roll and to space the outer surface of said cylinder a predetermined distance from the outer surface 25 of the film carried by said roll, said cylinder having a narrow longitudinal slot cut therein of a length substantially coextensive with the length of said cylinder, a spongelike member secured in said slot and extending radially outward from 30 said cylinder a distance greater than said predetermined distance and also extending into said cylinder to contact the internal surface thereof diametrically opposite said slot, a handle secured to one of said stub shafts for selectively rotating 35 said cylinder through an angle from an inoperative position where a plane including said slot and the axis of said cylinder is substantially vertical and said spongelike member is directed upward out of contact with said film to a position 40 where the radially extending portion of said spongelike member is in contact with said film, and liquid supplying means mounted on said machine and communicating with the interior of 45 said cylinder for uniformly distributing liquid throughout the length of said spongelike member and maintaining liquid in said cylinder at a level below the axis of rotation of said cylinder.
